UNITED STATES PATENT OFFICE

168,762

COMBINATION GRILL AND WAFFLE BAKER OR THE LIKE

John N. Polivka, Minneapolis, Minn., assignor to General Mills, Inc., a corporation of Delaware

Application October 30, 1952, Serial No. 22,064

Term of patent 14 years

(Cl. D81—10)

To all whom it may concern:

Be it known that I, John N. Polivka, a citizen of the United States, residing at Minneapolis, in the county of Hennepin, State of Minnesota, have invented a new, original, and ornamental Design for a Combination Grill and Waffle Baker or the like, of which the following is a specification, reference being had to the accompanying drawings, forming a part hereof.

In the drawings:

Fig. 1 is a top plan view of a combination grill and waffle baker or the like, showing my new design;

Fig. 2 is a side view;

Fig. 3 is a perspective view; and

Fig. 4 is a front view of the same.

The dominant features of the design reside in those portions shown in full lines.

I claim:

The ornamental design for a combination grill and waffle baker or the like, as shown and described.

JOHN N. POLIVKA.
